Car Seat and Couch.

No. 12,644.

Patented Apr. 3, 1855.

UNITED STATES PATENT OFFICE.

ALPHEUS D. SMITH, OF MEREDITH, NEW YORK.

RAILROAD-CAR SEAT.

Specification of Letters Patent No. 12,644, dated April 3, 1855.

To all whom it may concern:

Be it known that I, ALPHEUS D. SMITH, of Meredith, in the county of Delaware and State of New York, have invented a new and useful Improvement in Car-Seats; and I do hereby declare that the following is a full and exact description thereof, reference being had to the accompanying drawings, making a part of this specification, Figure 1 being a top view, Fig. 2 an end view, and Fig. 3 a vertical transverse section, of my improved car-seat when it is arranged for ordinary day-riding. Fig. 4 is a vertical transverse section of my improved car-seat when it is arranged for night-riding, and Figs. 5, 6, and 7 are views of detached portions of my improved car-seat.

The nature of my invention consists in making such additions to the ordinary form of car seat, that its back may be easily elevated and retained in the proper position for supporting the shoulders and head for night riding, or whenever it may be desired by the occupants.

The seat A, and the back B, of my improved car seat, are of the usual form. The arms c, c, which are secured to the ends of the back B, and which, in the ordinary day car seat, are pivoted to the arms k, k, in my improved car seat are jointed to the movable flat bars d, d, which pass through the inclosing guards l, l, on the facing plates h, h—that are secured to the inner sides of the seat arms k, k—and thence down through openings in the block e, e, which rest upon and are secured to the ends of the car seats, as shown in the drawings. When used as a day seat, the end bars d, d, are allowed to descend to the position shown in Figs. 2 and 3, which causes the arms c, c, of the back of the seat, to rest upon the inwardly projecting shoulders g, g, of the plates f, f,—that are secured to the supporters p, p, of the seat arms k, k,—and thereby the said back B, is securely held in its proper position for day riding.

When it is desired to put the back of the seat into the proper position for supporting the heads of the occupants of the seat, it is merely necessary to elevate the seat and the flat bars d, d, to such a height as to bring the pins j, j, which project outward from the

said bars, against the tops of the notches m, m, in the face plates f, f, on the seat arms k, k, when the requisite inclination can be given to the said bars d, d, to enable the lower corners of the back B, to rest upon the aforesaid shoulders g, g, as shown in Fig. 4; in which position the said back will be securely held by its arms c, c, and the flat bars d, d. As soon as the pins j, j, on the bars d, d, are brought in contact with the upper extremities of the notches m, m, in the plates h, h, the lower extremities of said bars can be moved forward or backward in the grooves i, i, in the blocks e, e, (shown in Fig. 7,) and thereby the requisite position be given to the said bars to sustain the back B, in its elevated position. The said bars d, d, are firmly held in their elevated positions by means of their lower extremities fitting into the ends of the grooves i, i, in the blocks e, e, in conjunction with their embracing guards l, l, and their pins j, j, fitting into the angles of the notches m, m, in the arm plates h, h.

To facilitate the change of position of the back B, from its elevated position to the position shown in Fig. 2, the bottoms of the grooves i, i, are inclined downward from their outer extremities toward the central apertures in the blocks e, e, that receive the bars d, d, when they are in the position shown in Fig. 2.

Having thus fully described my improvement in car seats, what I claim as new and desire to secure by Letters Patent, is—

The combination of the arms c, c, which project from the back of a car seat, with the movable bars d, d, which are combined with the car seat and its arms k, k, (or their equivalents) in such a manner that, by the aid of the shoulders g, g, on the standards p, p, the back of the seat may be supported in the proper position for day riding, or be elevated into the proper position for night riding, and supported in that position, substantially as herein set forth.

The above specification of my improved car seat, signed and witnessed this 15th day of November, 1854.

A. D. SMITH.
